[57] CLAIM

The ornamental design for combined alarm exit latch and lock therefor, as shown and described.

DESCRIPTION

FIG. 1 is a front elevational view of a combined alarm exit latch and lock therefor showing my new design, the rear being unornamented;

FIG. 2 is a bottom plan view thereof;

FIG. 3 is a side elevational view taken from the left of FIG. 1;

FIG. 4 is a side elevational view taken from the right of FIG. 1;

FIG. 5 is a fragmentary top plan view thereof;

FIG. 6 is a sectional view taken on line 6—6 of FIG. 2.
